(57) **CLAIM**

The ornamental design for washing high pressure equipment, as shown and described.

DESCRIPTION

FIG. 1 is a front, left side perspective view of the washing high pressure equipment showing my new design;

FIG. 2 is a front elevation view thereof;

FIG. 3 is a rear elevation view thereof;

FIG. 4 is a left side elevation view thereof;

FIG. 5 is a left side elevation view thereof;

FIG. 6 is a right and left side perspective view thereof;

FIG. 7 is a top plan view thereof; and,

FIG. 8 is a bottom view thereof.

The portion of the drawings appearing in broken lines is for illustrative purposes only and forms no part of the claimed design.
